DISPLAY STAND

Rudolf Orthwine, New York, N. Y.

Application October 14, 1939, Serial No. 299,487

1 Claim. (Cl. 35—53)

This invention relates to a display stand.

The object of the invention is the production of a display stand, by means of which various cloths, like silk, muslin, cotton and the like can be easily exhibited.

The second object of the invention is the production of a display stand with a front member having openings and a plate to the rear thereof to support a piece of material to be viewed through the openings of the front member, and means associated with the front member to detachably support the stand in operative position.

The third object of the invention is the production of a display stand for exhibiting various pieces of material in conjunction with the drawing of an object to which said material is adapted.

The fourth object of the invention is the production of a display stand, which is light in weight, cheap to manufacture and which does not require an expert to use.

In the drawing Fig. 1 represents a front elevation of the display stand; Fig. 2 shows a rear view of Fig. 1; Fig. 3 is a right hand side view of Fig. 2; Fig. 4 represents an enlarged section of Fig. 2, on the line 4—4; Fig. 5 shows an enlarged fragmentary portion of Fig. 2, and Fig. 6 is an enlarged fragmentary portion of Fig. 3.

The display stand comprises the front member 20, preferably of cardboard, and which has an opening designated in its entirety by the numeral 21. The card opening is shown with the outlines 22, 23, 24, 25, 26, 27, 28, 29, 30, 31, 32, and 33, and the dividing member 34, forming the contour of a dress in this instance. A human head is indicated on the outer face of the front member 20 at 35, arms are indicated at 36, legs at 37 and 38, and a hat at 39. All of the representations coact with the opening 21.

A rectangular opening 46 extends through the lower portion of the front member 20. To the rear face of the front member 20, are fastened by an adhesive, the longitudinal spacer strips 50. Each spacer strip 50 comprises the longitudinal upper portion having the inner edge 52 and the outer edge 53. The lower and wider portion of each spacer strip 50, is indicated with the inner edge 54. A horizontal supporting shoulder 57, is formed with each spacer strip 50 between its upper and lower portions. Through each of the spacer strips is formed a rectangular opening 60, for the slidable slat 62, with the knob 63 extending from the rear face thereof. The slat 62 has a legend indicated thereon which in this instance is John Doe & Co.

To each spacer strip 50 is fastened the rear strip 70, which has integral therewith and hinged thereto the tapered supporting leg 71. Strips of silk 71a and 71b, are fastened to the rear strips 50, and to the legs 71 and function as hinges to strengthen the connection between each rear strip 70 and its leg 71. It will be noted, see Fig. 2, that the lower end of the strip of silk 71a is spaced from the top end of the strip of silk 71b. The legs 71 are indicated in the drawing at right angles to the rear strips 70. In each tapered supporting leg 71, is indicated an opening comprising the upper portion having the curved edge 72 and the vertical edge 73, also the lower portion with curved edge 74, and the horizontal supporting edge 75.

For each strip 70 is shown a locking flap 80, which is hinged to its adjacent rear strip as indicated at 81. A portion 82 of each locking flap 80, is cut out from its adjacent rear strip 70, as indicated at 70a. The hinge portion 81 is strengthened by a hinge 81a which comprises a piece of silk cloth or the like, and the members of the hinge 81a are fastened to each flap 80, and its adjacent rear strip 70. Each flap 80 is also in hinged connection with the projection 83, which extends from the adjacent rear strip 70.

Attention is called to the fact that each rear strip 70 has integral therewith the projection 83, and each flap 80 is shown with its portion 82. The main portion of each flap 80 is hinged to the adjacent projection 83 and its portion 82 is hinged to its adjacent rear strip 70.

When the display stand is in operative position the supporting legs 71, as indicated in the drawing, are at right angles to the rear strips 70 and each locking flap 80, is in a horizontal position as shown and located to bear on its adjacent supporting edge 75. A rectangular plate is indicated at 90, and has connected to its rear face a pair of knobs 91. The plate 90 is slidably positioned between the front member 20 and the rear strips 70, see Fig. 4. The lower edge of the plate 90 is indicated at 92, and its side edges are indicated at 93. The lower edge 92, is adapted to bear on the supporting shoulders 57, and the side edges 93 bear against the inner edges 52 of the spacer strips 50.

A piece of cloth, silk or other material 100, is interposed between the plate 90 and the front member 20, and can be seen through the opening 21 of said front member 20. The piece of cloth 100, may be fastened to the plate 90, by thumb tack 102. The contour of the opening 21, in the front member 20, makes a good display of the

piece of cloth 100. Various pieces of cloth, one after the other, can be easily exhibited with the display stand.

When the display stand is not in use the locking flaps 80 are swung up to a vertical position and the tapered supporting legs 71 are located parallel to the plate 90.

It will be noted that the display stand may be made of cardboard, wood or any other suitable material.

Attention is also called to the fact that in place of the strips of silk 71a and 71b, and the hinges 81a of silk, metallic hinges may be used.

The plate 90 may be hinged to the member 20, instead of slidably thereto.

Various modifications may be made in the invention and the present exemplification is to be taken as illustrative and not limitative thereof.

Having described my invention, I claim:

In a display stand the combination of a front member having openings for the display of a piece of material, longitudinal spacer strips each with a horizontal supporting shoulder extending

from the rear face of the front member, a rear strip with a projection extending from each spacer strip, a rectangular plate slidably positioned between the front member and the rear strips, with the ends of its lower edge adapted to be supported on the shoulders of the spacer strips, a piece of material to be exhibited positioned opposite the rear face of the front member and carried by said plate, a supporting leg hinged on a vertical edge of each rear strip to swing rearwardly, each leg having an arcuate opening ending in a notch and a stop portion, and a flap hinged to each rear strip on a horizontal line and adapted to swing to a position normal to its strip and lying within said opening, each flap having a notch in its edge opposite the hinge, each opening adapted when its leg is swung outwardly to accommodate the outwardly swinging movement of the pivoted flap and receive the outer edge of said flap, said notches interengaging with each other, whereby the leg may be positively held in extended position.

RUDOLF ORTHWINE.
